UNITED STATES PATENT OFFICE.

IVORY L. HALL, OF VINAL HAVEN, MAINE.

DESIGN FOR A MATCH-HOLDER.

40,477.

Specification for Design.

Patented Feb. 1, 1910.

Application filed January 11, 1909. Serial No. 471,809. Term of patent 3½ years.

To all whom it may concern:

Be it known that I, IVORY L. HALL, a citizen of the United States, residing at Vinal Haven, in the county of Knox and State of Maine, have invented a new, original, and ornamental Design for Match-Holders, of which the following is a specification, reference being had to the accompanying drawings, forming a part thereof.

In the accompanying drawings, the figure is a perspective view of my match holder.

I claim:

The ornamental design of match holder, as shown.

IVORY L. HALL.

Witnesses:

A. C. PERKINS,
E. B. MACALLISTER.
